UNITED STATES PATENT OFFICE.

DAVID HINDAHL, OF CHICAGO, ILLINOIS, ASSIGNOR TO HARRY S. HART, OF CHICAGO, ILLINOIS.

HOPPER-CAR END AND LADDER CONSTRUCTION.

Application filed December 7, 1925. Serial No. 73,589.

This invention relates to an improvement in hopper cars of the type known as Maxend cars, shown for example in the patents to H. S. Hart No. 1,273,853, July 30th, 1918, and 5 to David Hindahl No. 1,453,675, May 1st, 1923, and has for its object to improve the sill step and ladder construction of such cars whereby the sill step may be placed in proper relation to the ladder without decrease of the load carrying capacity of the car. As is shown in the patents above referred to, these cars include side doors swinging outwardly over the trucks at the end of the car for the discharge of the load, 10 and it is essential in these cars, as in all hopper cars, that sill steps and ladders be provided which will comply with the requirements of the Interstate Commerce Commission. At the same time, it is desirable that 15 the load discharging doors should have as great length as possible in order to efficiently discharge the load, but the sill step limits the length which this door can have; moreover it is essential that the sill step be directly under the ladder so far as this is possible. In the patents above referred to, the sill step is placed considerably to one side of the ladder, making it difficult for the trainmen to pass easily from the sill step to the ladder. 20 The present invention overcomes this difficulty and provides an improvement in the method of forming an end recess at the car side for the purpose of receiving the ladder rungs. 25 According to the present invention, the top member of the auxiliary door frame is formed by a Z-bar introduced between the corner of the car and the nearest side stake, the dimensions of the Z-bar being such that 30 its web will define the proper depth of ladder recess in addition to providing the anchorage or arch for the vertically swinging auxiliary door and overhang from which the foot sill portion of the ladder may depend, and the 35 Z-bar being arranged with its upwardly presented flange next to the side plate which defines the outer surface of the car, and its downwardly presented flange offset horizontally inward a distance measured by the web 40 of the Z-bar, thereby producing the aforesaid pocket or overhang beneath which the hinges of the auxiliary door may be attached, the ledge or overhang beneath which the foot sill or bottom portion of the ladder is suspended, 45 and the recess for the upper portion of the 50 ladder, besides leaving the inner depending flange of the Z-bar as a protecting apron between the outflowing lading and the upper edge of the door and hinges; then, in order to permit use of the same continuous side 55 plate in the ladder recess as in the outer plane of the car wall, that portion of the outer and upwardly presented flange of the Z-bar corresponding to the width of the ladder recess is cut away, and the portion 60 of the side plate beyond the vertical Z-bar flange that is left is deflected inwardly and transversely to the car a distance corresponding to the depth of the ladder recess, and a distance sufficient to bring the deflecting portion of the plate in the vertical plane of the inner depending flange or leg of the Z-bar, in which plane said portion of the plate continues to the corner of the car. 65 And in order to develop a substantial corner construction, and one which will afford bolting facility for the ends of the hand irons, the said deflected portion of the side plate is continued in the inwardly offset plane thereof a sufficient distance beyond 70 the end plane of the car to afford a substantial riveting flange, and the end plate is bent outwardly to provide a corresponding riveting flange beyond the plane of the end plate; and these two flanges, riveted together, afford a substantial support for the 75 ends of the ladder irons and admit of locating the upper portion of the ladder over the lower or foot sill portion thereof. 80 In order that the invention may be fully 85 understood, the preferred embodiment thereof will now be described in detail in connection with the accompanying drawing, in which— 90 Figure 1 is a side elevation of an end portion of a railway hopper car, for which the selected illustrative embodiment of the invention is particularly designed. 95 Figure 2 is a section on the line 2^x—2^x of Figure 1. 100 Figure 3 is a horizontal section on the line 3^x—3^x of Figure 1; and 105 Figure 4 is a sectional detail view on the line 4^x—4^x of Figure 1. 110 1 represents the side wall; 2 a sustaining stake, 3 a portion of the main hopper bottom, and 4 the auxiliary side door which affords lateral escape for lading located in the end of the car beyond the main hopper 3 and in the position to reach said door 4 110

over the auxiliary hopper bottom 5. 6 represents the foot sill portion or depending member of a ladder construction which, because of the presence of the auxiliary door 4, is necessarily located at the extreme end of the car, and is of reduced width or dimension in the direction of the length of the car. It has heretofore been proposed to locate a structural member 7 between the extreme end of the car and the stake 2, and space said member upwardly from frame members 8 of the door a distance sufficient to provide a framing for the auxiliary door 4 and to afford mounting for the door hinges 9; also to provide a support from which the foot sill portion 6 of the ladder may depend.

According to the present invention, the framing member 7 is of Z-bar construction with an upwardly presented leg or flange 7^a in position to receive the inner face of the side plate 1, a horizontal web 7^b, and a downwardly presented leg or flange 7^c offset inwardly by said web. The width of the web 7^b is such as to adapt it to define the depth of a ladder recess 10 within the overall transverse dimension of the car, also to afford the desired overhang or place for hinges 9 and foot sill ladder section 6. It also presents the depending flange 7^c in a position to afford a guard between the outflowing lading and the upper edge of the door 4, as well as the hinges, as will best be seen in Figure 4.

As shown at 7^x in Figure 1, the upstanding outer flange 7^a of the Z-bar is omitted for a distance corresponding to the width of the ladder recess 10, so that the side plate 1 can be deflected around the end of the remaining portion of the flange 7^a to provide a side wall 1^a of the ladder recess 10, and thence, from the inner limit of said side wall, deflected longitudinally of the car to provide the back wall 1^b of the ladder recess 11 in the vertical plane of the inner face of the depending inner flange 7^c of the Z-bar; and in order to properly sustain these deflected portions of the side plate, the portion 1^b at the back of the ladder pocket is continued vertically downward over the inner face of flange 7^c, as shown at 1^c in Figure 2, and there secured by rivets 1^d (Figure 1).

In order to develop a substantial corner construction, the deflected portion 1^b of the plate 1 is continued longitudinally of the car beyond the end plate 11, and the latter, as shown more clearly in Figure 3, is deflected from the plane of the end of the car outwardly to provide a riveting flange 11^a to which the protruding portion of plate section 1^b is secured, as, for instance, by ladder rivets 12^a and such intermediate rivets 13 as may be desirable.

12 represents the hand irons which compose the upper portion of the ladder. These

may be of any approved design and they are secured by rivets 12^a, 12^b, of which the former, as already explained, pass through the corner flange 11^a and the lapped portion of plate section 11^b, while the latter pass through the plate section 1^b adjacent to the side wall 1^a of the ladder recess. A feature of the present invention consists in locating the attaching rivets 12^a, or equivalent means, at the extreme end of the car, as shown, with the advantageous effect of bringing the upper portion of the ladder, consisting of the hand irons 12, vertically above the foot sill portion 6, and corresponding avoidance of the hazard of missing the hand hold, which is a liability when the upper portion of the ladder, as heretofore, has been necessarily offset inwardly from the end in order to find a location for the rivets 12^a that would not interfere with the corner construction.

I claim:

1. In a car construction, a side plate member in an outer plane, a side plate member in a plane offset inwardly from said outer plane, and a Z-bar member having correspondingly offset flanges presented in position to receive the respective plate members, one of said plate members being deflected from the plane thereof toward the plane of the other plate member; and the Z-bar flange which receives the deflected plate member being cut away at the point of deflection.

2. In a car construction, a side plate member in an outer plane, a side plate member in a plane offset inwardly from said outer plane, and a Z-bar member having correspondingly offset flanges presented in position to receive respective plate members, one of said plate members being deflected from the plane thereof toward the plane of the other plate member; and the Z-bar flange which receives the deflected plate member being cut away at the point of deflection and beyond the same a distance corresponding to the width of said other plate member.

3. In a car construction, a plate deflected to provide integral plate members in outer and inner planes offset one from the other, and a Z-bar member having a flange extending in one direction in a plane to receive one of said plate members, but cut away from and beyond the plane of deflection between the plate members and having another flange presented in the opposite direction in a plane to receive the other plate member; said other plate member being extended a distance sufficient to overlie the second named flange.

4. In a car construction, a Z-bar frame member having a horizontal web and vertically but oppositely extending flanges plate members in the planes of the respective flanges but offset one from the other by the distance of the web of the Z-bar and pro-

viding by such offset a ladder recess, and ladder members located in said recess.

5. In car constructions, a Z-bar having a substantially horizontal web and flanges extending vertically but in opposite directions from said web, and in planes offset by the width of the web, a door mounted upon said frame member, an outer plate secured to one of said flanges, another plate offset a distance corresponding substantially to the width of the said web and secured to the other of said flanges, thereby providing a ladder recess, and ladder members located in said recess.

15. 6. In car-body constructions, wall plate members in planes offset inwardly one from the other and providing a ladder recess, an intersecting wall plate member, the plate member in the inwardly offset plane having a continuing portion beyond the plane of said intersecting wall plate member, ladder members and sill step members secured to said continuing portion.

7. In car-body constructions, wall plate members in planes offset inwardly one from the other and providing a ladder recess, an intersecting wall plate member, the plate member in the inwardly offset plane having a continuing portion beyond the plane of said intersecting wall plate member, said intersecting wall-plate member having an out-turned flange lapping upon said continuing portion, ladder members and sill step members secured to said continuing portion and lapping flange.

8. In railway car-wall constructions, wall plates lying in planes offset inwardly one from the other, a wall plate intersecting the inwardly offset wall plate, said inwardly offset wall plate having a continuing portion beyond said intersecting wall plate, and said intersecting wall plate having an out-turned flange lapping upon said continuing portion, and a frame member having flanges offset inwardly one from the other and secured respectively to the outer and inner wall plates; one end of said frame member being secured to said continuing portion and lapping flange.

50. 9. In railway car-wall constructions, outer and inner wall plates lying in planes offset inwardly one from the other, a wall plate separating the inwardly one from the other, a wall plate intersecting the inwardly offset wall plate, said inwardly offset wall plate having a continuing portion beyond said intersecting wall plate, and said intersecting wall plate having an out-turned flange lapping upon said continuing portion, a stake

to which the outer wall plate is secured, and a frame member having flanges offset inwardly one from the other and secured respectively to the outer and inner wall plates; one end of said frame member being secured to said continuing portion and lapping flange, and the other end thereof being secured to said stake.

10. In railway car wall constructions, a frame member comprising a web portion and vertically extending outer and inner flange portions offset by said web-portion one inwardly from the other, a door hinged to said frame member, outer and inner wall plates offset one inwardly from the other, secured respectively to the outer and inner flanges and providing, by their offsetting, a ladder recess, a wall plate intersecting said inner wall plate, said inner wall plate having a continuing portion beyond the plane of intersection of said intersecting wall plate, upper ladder members in said ladder recess having their ends secured to said continuing portion, and a lower ladder member located between said door and the car end and depending from said frame member; said upper ladder members being vertically above said lower ladder member.

11. In railway car wall constructions, a frame member comprising a web portion and vertically extending outer and inner flange portions offset by said web-portion one inwardly from the other, a door hinged to said frame member, outer and inner wall plates offset one inwardly from the other, secured respectively to the outer and inner flanges and providing, by their offsetting, a ladder recess, a wall plate intersecting said inner wall plate, said inner wall plate having a continuing portion beyond the plane of intersection of said intersecting wall plate, said intersecting wall plate having an out-turned attaching flange lapping upon said continuing portion, upper ladder members in said ladder recess having their ends secured to said continuing portion and to the out-turned lapping portion of the intersecting wall plate, and a lower ladder member located between said door and the car end and depending from said frame member.

12. A car of the class described having a side wall extended beyond the end wall and ladder rungs and a sill step secured at one end to the extended portion of the side and at their other ends to the car body.

Signed at Chicago, Illinois, this 3d day of December, 1925.

DAVID HINDAHL.
